BOOKCASE AND LIKE SHELVING

Harold Irwin, Tikokino, Waipawa, Hawkes Bay,
New ZealandApplication July 5, 1945, Serial No. 603,365
In New Zealand August 15, 1944

3 Claims. (Cl. 211—136)

1

This invention has been devised with the object of providing for the formation of such structures as bookcases, showcases, shop storage shelves and so on, in which the structure is formed by means of combined shelving and supporting frames.

The purpose for which the invention has been designed is to provide for the construction of the frame and shelving and their combination with fittings in such a manner and of such a nature that the structure may be assembled or disassembled at will, and in the assembly the spaces between the shelves may be varied in height, or altered from time to time as required. In addition, provision is made for the spaces between the shelves being divided off in their length by vertical division pieces which may be readily adjusted to different positions along such length.

Thus the invention allows for the parts to form the structure, being packed within a minimum of space for storage and (or) for transport, as the unit members of the structure may be arranged flat, one upon the other when in the disassembled condition.

The invention is applicable in respect of its characteristic features to the formation of the shelving from sheet metal to produce a complete metal structure, but is also applicable to a combination in which the frame and shelving are made of wood and the assembly fittings of metal.

In describing the invention reference will be made to the accompanying drawings, in which:

Figure 1 is a front elevation of a set of shelving as assembled for use, the lower part thereof being shown in section.

Figure 2 is an inside elevation of one of the main upright frame members, showing a shelf in section associated therewith.

Figure 3 is a sectional plan of Figure 1.

Figure 4 is a detail view showing two of the shelves in cross section and a divisional plate associated therewith.

Figures 5, 6 and 7 are detail views illustrating the application of the invention to wooden framing and shelving of which Figs. 5 and 7 are sectional views and Fig. 6 is a side elevation.

In the illustration of the invention as concerned with the all metal construction shown in Figures 1 to 4, for purposes of clearness in understanding the sheet metal is shown of much

greater relative thickness than would ordinarily be required as owing to the manner of forming and combining the parts the necessary strength and stability of the structure may be obtained by employing thin metal sheeting of steel or like nature.

Also, in the making of the parts composing the shelving, the ordinary and well known practices in the art concerned with the shaping, joining and fabricating of sheet metal are employed.

The construction of shelving comprises in its main features, the provision of vertical side frame forming units 10 and horizontal principal upper and lower shelf units 11 and 12 adapted to be locked at their ends with the side units 10 to form a rigid rectangular frame enclosure. It also comprises a number of intermediate shelf units 13 extending between the side units and supported at their ends by novel means which allow for these shelves being adjusted at any level in the frame that may be desired. In addition, the structure provides for the use of vertical division plates 14 for combination with the shelves to divide off the shelf spaces into separate divisions and for these plates being adjusted and held at any desired point along the length of the shelves.

Each of the said side frame members 10 is provided, near its top and bottom and upon its inside face, with a ledge 15 arranged in a groove 16 extending right across its width so that it projects vertically upward in the surface plane of the member and at its upper portion is a distance out from the groove face. Each end of each of the said upper and lower principal shelf units 11 and 12 is provided, or constructed with a downwardly turned lug 17 extending across the full width thereof and this is designed to slide in along the said ledge 15 to thus lock the shelf end to the side member, thereby providing for these two shelf members being arranged to extend between the side members in an interlocking manner. When the said members are made of wood as in Figure 5, the ledge 15 upon the side 10' may suitably be formed by a flat strip of metal secured over the groove 16' formed in such side, while the lug 17' on the shelf 11' may be formed of metal plate shaped to extend up the edge of the shelf and fastened thereto and turned over into hook form at its top, and also,

if desired, shaped with extensions on its inner part which lie beneath the shelf end to more effectually support it. The frame thus made may be re-inforced to aid its rigidity by corner metal brackets 18 extending across the back edges of the joints made by the engaging members. Also, the shelf member 11 may be fastened in position by using screws to pass out through the said ledges 15 and into the lugs 17 upon the shelf members.

Each side member 10, Figs. 2 and 3, of the frame is also formed or provided with two vertical slots 20 extending between the upper and lower shelf jointing, such slots being disposed one near each edge of the said member.

In the metal structure shown in Figures 1 to 4 these slots 20 are formed in the side member itself and in the wooden structure shown in Figures 5 to 7 the slots are formed in metal plates 21 that are imbedded into the surface of the side member in grooves formed in such surface. Each slot 20 and 20' is made with notches 22 and 22' formed at suitable intervals along the length of its back edge which notches open from the slot and turn down for a distance as shown in Figures 2 and 6. With the metal side members shown in Figures 1 to 3 the slots 20 may each be closed or covered over on its outside by means of a metal strip suitably secured to the surface of the member 10.

The intermediate shelves 13 are designed to be supported in the side members 10 and to be adjusted up or down to any desired position by forming or providing each shelf at each of its ends with two longitudinally extending pin projections 23 which are positioned apart in the width of the shelf a distance corresponding to the distance between the slots 22 in the latter. These pins enter the respective slots at each end of the shelf and are adapted to slide up and down therein and then to be caused to engage and rest in any of the notches 22 as desired, by merely moving the shelf slightly rearward and releasing the shelf. At any time the shelf may be freed from such engagement and raised, or lowered, and then again engaged and supported at the required level.

In the case of a metal shelf as in Figures 1 and 3 these pins 23 may be formed upon the ends thereof, which ends may be flanged, as shown, to strengthen them. The front and rear edges of the shelf may also be flanged as shown. In the case of wooden shelving as in Figure 5, the pins 23' are formed upon a metal strip 28, Fig. 7, that is screwed, or otherwise fastened to the end edge of the shelf, or the pins may be driven into the edge itself.

For the fitting of the adjustable vertical divisions 14 to extend between the shelves, each shelf on each of its faces is made with a slot 24 extending longitudinally along near each edge and made with notches 25 opening at right angles therefrom at intervals apart in such length. The notches 25 of the two slots extend in the same direction relatively to the back and front edges of the shelf with those of the one slot opposite those of the other, and these slots on the one shelf are made in exact alignment with those on the others in a standardized manner. The division pieces 14 extending between the shelves may be made of varying heights to correspond with the adjustments made in the positions of the shelves in the frame. Each of these pieces is formed, or provided, with two pins 26 projecting from its bottom and top edges and positioned

at distances apart corresponding with the distance between the slots of the shelf faces. Thus a division piece may be placed in position by canting it sideways and then straightening it up to cause the pins on its top and bottom to enter the slots of two adjacent shelves and it may then be slid along to any point, and locked from movement at any desired position by moving it laterally to cause its pins to enter notches branching from such slots, the notches in the one slot being opposite those in the other.

In the all metal form the slots 24 for the top and bottom frame forming shelves 11 and 12 are cut in the metal sheeting, while in the intermediate shelves 13 those for the upper side are cut in the sheeting and those for the lower side are formed in flat strips 27 arranged along beneath the upper slots so as to make their slots coincident as shown in Figure 4. The pins 26 upon the metal division plates 14 are made integrally with the formation of the plates.

With wooden shelves and division pieces, however, the said slots (as shown in Figure 7) are formed in metal strips 28 imbedded into the surfaces of the shelves, and the pins 26 are formed upon metal plate strips 29 secured along the top and bottom edges of such pieces, or instead these pins may be driven directly into the wood.

The construction of the various parts lends itself to a system of standardization in manufacture, and also in respect of wooden shelving to the manufacture and supply of the metal parts for use by makers of the wooden parts.

Any appropriate provision may be made to supply the assembled structure with a back if so desired.

I claim:

1. Bookcase or the like forming shelving comprising two vertical end frame members each having horizontal ledges extending across its width respectively near its inner upper and lower ends, said ledges lying within the plane of the inner surfaces of said end frame members, said end frame members having recesses provided behind said ledges, upper and lower shelf units disposed to extend horizontally between the end frame members and each provided with downwardly turned lugs on their ends, said lugs extending over the respective ledges on the end frame members and into said recesses, to thereby form a rectangular framing, screws carried by said ledges and cooperating with said lugs for securing the shelf units in place, and intermediate shelf members extending between the main frame members and supported thereby by means permitting the shelves to be adjusted in their height within the said framing.

2. Bookcase or the like forming shelving according to claim 1, in which each of the said end frame members is provided with slots extending parallel and vertically along its inner face, each of said slots being formed with spaced notches, and in which each intermediate shelf is provided with pins projecting from its end adjacent to each end member to project respectively into the slots and the notches thereof.

3. Bookcase or the like forming shelving, comprising a plurality of shelves each of which is provided with slots extending parallel along each face and lengthwise of the shelf and each slot having notches opening at intervals in its length from the back edge thereof, and vertical division pieces adapted to extend transversely between the shelves and each being provided with pins

projecting from its upper and lower edges and positioned as to pass respectively into the said slots and to slide along the slots and into the said notches.

HAROLD IRWIN.
